DROP HAMMER

Application filed May 25, 1931. Serial No. 539,933.

The invention relates to drop hammers of that type in which the hammer block is lifted by the frictional engagement of driven rollers with a board shank, the frictional engagement being released at a predetermined point in the upward travel of the block to permit the falling of the same and the delivery of the hammer below. It is the object of the present invention to obtain a construction with which the height of the lift and consequently the force of the blow may be varied and without the necessity of stopping the machine. To this end the invention consists in the novel construction as hereinafter set forth.

In the drawings:

Figure 1 is a front elevation of my improved machine;

Figure 2 is a sectional side elevation thereof;

Figure 3 is a diagram showing a modified construction.

Drop hammers of the type above referred to have long been used in the art and in general construction comprises a bed or anvil A, spaced upright frames B and B', a cross head C at the upper end of these frames, friction rolls D and D' mounted on this cross head, a hammer block E and a board shank F secured at its lower end to said hammer block and passing upward between the rolls D and D'. The rolls D and D' are journaled in eccentric bearings G and G' which are provided with actuating rock arms H and H' for adjusting the same to move their peripheral faces towards or from the board F. The rock arms H and H' have connected thereto rods I and I' which extend vertically downward at one side of the frame and from weights for rocking the arm H H' downward to produce the desired friction between the rolls D and D' and shank F. One of the rods I' is provided at its lower end with a threaded portion passing through an apertured

bracket J on the frame B' and having adjusting nuts J' thereon by which it may be raised or lowered. The other rod I extends through a bearing K having a shank K' laterally slidably mounted on the frame B and resiliently drawn inward by the tension of a

spring K². Above the bearing K the rod I has adjustably clamped thereto a collar L which in certain positions of the rod is adapted to engage with the roller bearing shelf M on the frame B', thereby holding the rod in raised position and through the medium of the rock arm H an eccentric G withdrawing the roller D from frictional contact with the board shank F. When, however, the collar L is disengaged from the shelf M the rod I moves downward and its weight is sufficient to produce the desired friction between the roller D and the shank F. For raising the rod to engage the collar L from the shelf M there is provided a lever N pivoted at N' on the frame B' and extending adjacent to the path of the hammer block E when lifted by the shank F. A pin N² on the hammer block engages the lever N to rock the same upward. There is also a collar O clamped upon the rod I and engaging the lever N so that the rocking of the latter will lift the rod I permitting the collar L to engage the roller shelf M. For disengaging the collar L from the shelf M an arm P clamped to the rod extends adjacent to the path of the block E near the lower end of its travel and a cam P' on this block engaging the arm P will move said arm and the rod I and bearing K outward against the tension of the spring K², thereby disengaging the collar L from the shelf M.

To hold the hammer block in raised position when the machine is not in operation, there is provided a locking mechanism comprising rockable friction dogs Q and Q' mounted on the cross head C and arranged upon opposite sides of the board shank F. These dogs are adapted whenever released to clamp the shank F and to hold the same and the hammer block E suspended thereon from downward movement. The dogs may, however, be released by the operation of a treadle R which is connected through the medium of rods S and S' with said dogs Q and Q' so that whenever the treadle is depressed the dogs will release the shank F permitting the hammer block to fall.

The construction as thus far described is old and well known in the art and operates as follows: The rollers D and D' are driven by

pulleys T and T' or any other suitable drive connection so as to revolve in opposite directions with portions of their peripheries adjacent to or contacting with the board F, traveling in an upward direction. The normal position of the rod I is with the collar L resting on the roller shelf M and the normal position of the dogs Q and Q' is in engagement with the shank F when the hammer block 10 E is in raised position. To start the machine and deliver a blow the treadle R is depressed which through the medium of rods S and S' releases the dogs Q and Q' and as the rollers D and D' are not in frictional engagement with the shank the block E will drop, delivering the blow upon the work supported by the bed or anvil A. During the descent of the block E the cam E' thereon engaging the arm P will move the same outward, disengaging the collar L from the shelf M and permitting the rod to fall. This will move the roller D into frictional engagement with the shank F and as both rollers D and D' are constantly rotating, the shank will be driven 20 upward, lifting therewith the hammer block E. When, however, the pin N² engages the lever N, this lever will be rocked and through its engagement with the collar O will lift the rod I, whereupon the spring K² drawing 30 the bearing K inward will engage the collar L with the shelf M. This again releases the shank, permitting the hammer block to drop and this operation will be repeated as long as the treadle R is held depressed. However, if the treadle is released the dogs Q and 35 Q' will be permitted to engage the shank F to hold the same in raised position.

To adapt the machine for different variations of work provision is made for adjusting the lever N and collar O so that the hammer block may be released from this elevation above the anvil. This will correspondingly change the force of the blow delivered but to make such an adjustment it 45 is necessary to stop the machine. Moreover, considerable time is required in effecting the adjustment during which the machine remains idle. With certain constructions manually operable means has been provided for lifting the rod I to release the friction roll D, but on account of the weight of the parts and the consequent large inertial factor, it is difficult or impossible for the operator to make use of this means to vary the force of 50 the blow during operation of the machine. It is therefore the primary object of my invention to provide means for varying the stroke of the hammer which requires no labor on the part of the operator. It is a further object to accomplish this result in such a manner that the operator may control the machine during its operation so that successive blows may be either light or heavy, according to the requirements of the work. 55 My improvement consists essentially in a

power motor for lifting the rod I, which is under the control of the operator but which is automatically timed in its operation to cooperate with the hammer block E. Various specific constructions may be used for accomplishing the desired result but as shown, I employ a pneumatic motor comprising a cylinder U and piston U' mounted on the bed A or otherwise secured to be arranged beneath the rod I. The movement of the piston within the cylinder is controlled by a valve V which in turn is operated by a solenoid W. This solenoid is arranged in an electric circuit which includes a switch or circuit closer W' arranged to be actuated by the treadle R when depressed further than necessary for releasing the dogs Q and Q'. The electric circuit also includes a switch or circuit closer W² which is mechanically actuated by the hammer block E during its upward movement. Thus the electric circuit is closed and the solenoid W energized only when both of the switches W', W² are closed, the former being under the control of the operator and the latter being automatically actuated. The switch W² as shown in Figure 1 is mounted upon a plate X which in turn is vertically adjustably mounted on the frame B. The switch is actuated by a rod X' laterally slideable in a bearing X² on the plate and having a roller X³ which extends into the path of a cam X⁴ on the block E. Thus the upward movement of the block E will cause the cam X⁴ contacting with the roller X³ to move the rod X', thereby closing the switch W², and if the treadle R has been previously depressed to a position where it will close the switch W', the solenoid W will be energized, operating the valve V to admit compressed air into the cylinder U. This by raising the piston U' will lift the rod I permitting the collar L to engage with the roller shelf M. Consequently the hammer block instead of being lifted to its full height will drop from the point where the switch W² is located, this being varied by adjustment of the plate X on the frame B.

In the practical operation of the hammer for performing most work, it is not necessary to have more than the two strengths of blow, the one delivered by the raising of the hammer block into engagement with the lever N and the other by releasing the block upon the closing of the switch W². If, however, it is desired to have more than these two strengths, this may be accomplished by arranging a series of switches W³, W⁴, W⁵, and actuating means therefor located at different elevations above the anvil. The particular one of these switches to be used may be controlled by a selective switch Y which is under the control of the operator, as shown in Figure 3. With this modification the operator still controls the operation by the treadle R but by 130

adjusting the selective switch Y may change the strength of the lighter blow as desired.

One of the advantages of my construction is that it requires no modification of the standard construction of hammer which normally functions in the same way as heretofore. The added elements are entirely distinct from those of the standard construction and if desired may be mounted on a separate frame. However, as shown, these elements are mounted on the main frame but at points where they do not interfere with any of the working parts of the standard machine.

To avoid any interference to the dropping of the rod due to lag in the operation of the pneumatic motor, I preferably provide auxiliary means for instantaneously de-energizing the solenoid W and shifting the valve V upon engagement of the collar L with the roller M. This comprises a circuit breaker Y which is in series with the switches W', W² and which is mechanically actuated by the rod I when the latter is engaged or disengaged from the shelf M. The arrangement is such that the circuit is closed when the rod I is down or disengaged from the shelf, but is open when the rod is supported by engagement of the collar L with the roller M. Thus as soon as the rod I is raised by the piston U' so that the collar L engages the roller M, the solenoid W will be de-energized which by shifting the valve V will drop the piston U', permitting the rod I to fall freely when released by the arm P.

What I claim as my invention is:

In a drop hammer of the type comprising friction means for lifting the hammer block and a control rod and cooperating means for automatically effecting the engagement and release of said friction means for a predetermined length of stroke of the hammer, of an auxiliary pneumatic motor for lifting said rod, electro-magnetic means controlling the operation of said motor, a circuit closer for the circuit of said electro-magnetic means operated at a predetermined point in the upward movement of the hammer block less than its full stroke whereby said motor will lift said rod, and a circuit breaker also controlling said circuit for de-energizing said electro-magnetic means at the completion of the raising of said rod.

In testimony whereof I affix my signature.
RUSSELL E. WALDRON.
